[57] CLAIM

We claim the ornamental design for a slot machine cabinet, as shown and described.

DESCRIPTION

FIG. 1 is a right front perspective view of a slot machine cabinet, showing our new design;

FIG. 2 is a rear view thereof;

FIG. 3 is a top view thereof;

FIG. 4 is a left side view thereof; and,

FIG. 5 is a right side view thereof.

FIGS. 2-5 are shown on a reduced scale.

The broken line drawings of the gaming machine, including portions of the display portion, are to show environment only and such environment is not being claimed.
